SPARK ADVANCE INDICATOR

Brooks H. Short, Anderson, Ind., assignor to General Motors Corporation, Detroit, Mich., a corporation of Delaware

Application October 21, 1940, Serial No. 362,111

1 Claim. (Cl. 177—311)

This invention relates to devices for indicating spark advance for internal combustion engines.

The object of the invention is to provide electrically operated apparatus controlled by the 5 sparking at a spark plug for causing a properly calibrated electric meter to read directly in degrees of spark advance. In the disclosed embodiment of the present invention, this object is accomplished by providing a D. C. source of constant voltage which will cause a constant direct current to flow through an electric current meter, by providing means automatically responsive to sparking at an engine spark plug for establishing said current flow and by providing means automatically responsive to top 10 dead center position of the engine piston for interrupting said current flow. The meter will give a reading which varies in accordance with the duration of the current flow; hence, the 20 meter, when properly calibrated, will give a reading in degrees of spark advance ahead of top dead center.

Further objects and advantages of the present invention will be apparent from the following description, reference being had to the accompanying drawing wherein a preferred embodiment of the present invention is clearly shown.

In the drawing:

Fig. 1 is a wiring diagram of the spark advance indicating apparatus.

Fig. 2 is a diagram of operation of the apparatus.

The current source of constant voltage is obtained by connecting, between the line wires 10 and 11 of a 220 volt D. C. generator, a voltage divider system comprising five type VR 150 voltage regulator tubes TU₁, TU₂, TU₃, TU₄ and TU₅ connected in parallel, with a 100 ohm, 2 watt 40 equalizing resistor in each tube circuit. These resistors are marked R₁, R₂, R₃, R₄ and R₅. The resulting parallel combination is connected in series with a 500 ohm, 20 watt fixed resistance R₆ which functions to absorb increased voltage. The operation of this combination is to maintain a constant voltage of 150 volts across the parallel combination, even when the load current varies between .15 amp. and .025 amp.

M is a D. C. milliammeter originally intended to read from zero to 5 ma. It is calibrated to give a reading in degrees of spark advance.

The means which automatically establishes current flow through meter M at the instant of 55 sparking is the thyratron TU₇ which may be one

of the type 2050 thyratrons. Tube TU₇ is normally nonconducting since its grid is normally negatively biased by 3 volt battery BA₁. At the instant of sparking in the #1 or any other engine cylinder, the grid bias of tube TU₇ becomes zero or positive thereby causing this tube to become conducting. It will remain conducting until its plate circuit is interrupted by rotary or slip ring switch SR having a brush 12 and a conducting segment 13 of such length as to be in contact with brush 12 at the time of any possible sparking ahead of top dead center but to separate from the brush 12 at the instant the engine piston reaches top dead center. Obviously segment 13 is rotated by any conveniently accessible engine driven part such as the crank shaft (not shown.) Rotary switch SR constitutes the means for causing tube TU₇ to interrupt the current flow to the meter M.

The voltage of #1 spark plug (or any other, 25 spark plug) is picked up by a very small capacity C₁ (10 m. m. f., 30,000 v.) and is introduced through a variable resistance R₇ (1000 ohm potentiometer or voltage divider) to the grid of an amplifier tube TU₈ which may be a type 6A6 or a 6N7. The output of amplifier TU₈ is coupled by transformer T₁ (T84 D59 Thordarson) to the grid of thyratron TU₇. Although the initial lobe of the secondary voltage is negative 30 with respect to ground, the impulse of voltage sent to the thyratron grid is positive. This impulse causes the thyratron grid to ionize the gas in tube TU₇ so that plate conduction results. The current flow to meter M immediately reaches maximum as soon as the spark plug fires and will continue at that value indefinitely until the plate voltage is removed. The plate voltage is removed when the engine reaches top dead center thereby causing segment 13 to be separated from brush 12 at that instant. The current has been flowing at its constant peak a—b (see Fig. 2) throughout the time between the firing of the spark-plug and top dead center "T. D. C." As the current is constant during 35 the advance period, the time integral of current a—c (Fig. 2) over a complete cycle of engine operation (720° crank shaft degrees between successive firings of the same spark-plug) will be directly proportional to the degrees of spark 40 advance. Therefore, the meter M in the thyratron plate circuit can be calibrated directly in degrees of spark advance.

In order that the meter M will be accurate the 45 value of current flowing in the thyratron plate circuit during the spark advance period must

be set very accurately. This is accomplished by moving the contact arms 14, 15 and 16 of useal. switch SW₁ from "use" positions (full lines in Fig. 1) to "cal" (calibrate) positions 14', 15' and 16'. (Dotted lines in Fig. 1), thereby causing zero voltage to be placed on the thyratron grid (which makes the thyratron conducting), the slip ring switch S. R. to be shorted out, and a resistance R₁₀ (to suit the meter M) to be placed in shunt with the meter M.

Resistance R₉ (1500 ohms, 20 watt variable resistance) is adjusted until the meter M reads at a predetermined set position. That predetermined position or calibration mark on the meter dial has been obtained in the following manner. Let it be assumed, for example, that one wishes to use an ampere meter reading from zero to 5 milliamperes on its scale to indicate, on the same length of scale, zero to 80° of spark advance. This means that, when the meter reads 80° spark advance, the time integral of current *a*—*c* (Fig. 2) over an engine cycle of 720° crank shaft degrees will be 5 m. a. The actual value of current *a*—*b* (Fig. 2) flowing in the thyratron plate circuit during a spark advance period of 80° will be $720^\circ/80^\circ \times 5 \text{ m. a.} = 45 \text{ m. a.}$

In order to make this same 5 m. a. meter M give a reading of 45 m. a. a suitable resistance R₁₀ is placed in shunt therewith. Electric current known to have the value of 45 m. a. is passed through the meter M and shunt R₁₀ and a calibration mark is placed on the dial of meter M to indicate when 45 m. a. is flowing to the meter M and shunt R₁₀. With the meter M and shunt R₁₀ in the circuit shown in Fig. 1 and with the switch SW₁ in "cal" (calibrating) position, resistance R₉ controlling the value of current then flowing continuously in the plate circuit of the thyratron is adjusted until the pointer of meter M coincides with the calibration mark indicating 45 m. a. current flow. Obviously, if one wished to use a 5 m. a. meter to give reading of 0° to 60° spark advance, the calibration mark would be $720/60 \times 5 \text{ m. a. or } 60 \text{ m. a.}$

The meter readings are proportioned to spark advance provided the current in the plate circuit remains constant. For example, if the passage of 45 m. a. of current through the plate circuit during rapidly recurring periods of 80/720 of the engine cycle gives a read of the 5 m. a. or 80° spark advance on the meter dial, the passage of this same amount of current during rapidly recurring periods of 40/720 of the engine cycle will give a meter reading only one-half as great namely, 2.5 m. a. or 40° spark advance.

Before beginning to take a series of readings of spark advance, the switch SW₁ should be moved to calibrate position and the resistance R₉ should be adjusted if necessary so that the pointer of meter M will point to the calibration mark. Since the time of a previous use of the apparatus, conditions may have arisen to change the value of current in the plate circuit of the thyratron.

These conditions may be, for example, variation in temperature of the air surrounding the voltage regulating tubes TU₁ to TU₅, ageing of the tube TU₇. Therefore calibration is required to be sure that meter M gives the correct direct reading in degrees of spark advance.

The electrical dimensions of units not heretofore given are as follows:

Resistance R₈—800 ohms, 10 watt (functions to 10 put a negative bias on the grid of amplifier tube TU₆).

Condensers C₂ and C₃—8 m. f.—450 v. electrolytic condensers.

Battery AA—6 volt battery (for heating tubes 15 TU₆ and TU₇).

While the embodiment of the present invention as herein disclosed, constitutes a preferred form, it is to be understood that other forms might be adopted, all coming within the scope of the 20 claim which follows.

What is claimed is as follows:

A spark advance indicating system comprising a D. C. ammeter constructed to give a current reading of zero to *x* milliamperes and provided 25 with a dial to give a spark advance reading of zero to *y* degrees, the reading of *y* degrees corresponding to the reading of *x* milliamperes, said dial bearing a calibration mark to indicate the flow of

30

$\frac{xx}{y}$

milliamperes, *z* being the number of degrees of rotation of the engine crank shaft during the 35 cycle of engine operation; a resistance to be placed in shunt with the meter to obtain the calibration mark; a "use" or operating circuit comprising a current source of constant potential, a thyratron tube for connecting the meter with the current source, means responsive to occurrence of sparking at an engine plug for causing the tube to become conducting and means responsive to top dead center of the engine piston 40 associated with said spark plug for causing the meter to be disconnected from the current source; and a calibrating circuit comprising the current source, the tube, the meter, the resistance shunting the meter and a variable resistance for adjusting the continuous current flow 45 through the plate circuit of the tube so that the meter pointer will point to the meter calibration mark; and a circuit controller including a manually operated member having a "calibrating" position in which both of the aforesaid means are rendered non-operating and the meter and 50 its shunt resistance are connected in parallel and both together in series with the tube and current source and the tube grid is brought to zero voltage to make the tube conducting, and having a "use" position in which both of the aforesaid 55 means are rendered operating and the meter-shunt-resistance is open circuited.
